UNITED STATES PATENT OFFICE.

BENJAMIN HOFFMAN, OF SOUTH BELOIT, ILLINOIS, ASSIGNOR TO PARAMOUNT TEXTILE MACHINERY CO., OF CHICAGO, ILLINOIS, A CORPORATION OF ILLINOIS.

KNITTING MACHINE.

Application filed February 19, 1926. Serial No. 89,404.

This invention relates, primarily, to knitting machines; and it has particular reference to the type thereof in which the needle-cylinder is raised and lowered to vary the 5 length of stitch produced therein; and it involves a controlling-device therein for positively maintaining, in a predetermined position, mechanism that operates automatically to vary the length of the stitch in a course.

10 My inventive-concept—involving an attachment, in one aspect thereof—is especially applicable to circular knitting machines of the so-called "Scott & Williams" type, as exemplified in United States Patent 15 No. 1,152,850, dated September 7, 1915, of R. W. Scott, for knitting seamless hosiery.

In the accompanying drawings, I have illustrated one of many embodiments of the structure; but it is to be understood that 20 my inventive-concept is susceptible of other embodiments and utilizations and also of a wide range of modification and variation without departing from the principles of the invention or sacrificing any of its salient and 25 underlying features.

In these drawings, which show the device applied to a machine of the type illustrated in the above-mentioned Scott patent:

Figure 1 is a view in vertical section 22 through the needle-cylinder, column, and sinker-cam-ring of the machine, with certain parts omitted more clearly to illustrate my controlling-device and its relation to other mechanisms of the machine;

35 Fig. 2 is a view in plan and somewhat fragmentary;

Fig. 3 is a view in perspective of the device, showing its operating relation to the sinker-cam-ring;

40 Fig. 4 is a fragmentary view, in central vertical section, of the device; and

Fig. 5 is an enlarged, sectional view of the presser-element of the device.

In the aforementioned Scott & Williams 45 type of machine, certain parts thereof—such as the needle-cylinder or carrier—by reason of their arrangement, are capable of rotative and reciprocal movements with respect to a relatively fixed base and actuating cams 50 thereon that influence the action of the needles in the cylinder. The construction is such that the movable cylinder and its adjunctive parts may "float", so to speak, with respect to the base and cams. Due to this 55 fact, it not infrequently occurs that, for one

or another of several reasons, the cylinder is not in its proper position and this varies to an extent that the needles carried thereby are caused to draw too much yarn, in consequence of which the fabric, at certain portions, is too loosely knit. It will be evident that if this loosely-knit fabric occurs during the production of the ankle or instep sections of the stocking, an undesirable product is produced.

Due to the law of operation of the machine, it seems to have been found essential to construct it so that the needle-cylinder and its adjunctive parts would tend to return toward their lowest positions by gravity and it is because of this that the "floating" condition is liable to occur if and when gravity is not sufficient to overcome the resistance to movement of the parts. The cylinder is pushed up positively by a column 70 operating under the influence of the pattern-drum. When the position of this drum is changed to lower the cylinder, the column is free to fall by gravity, and the cylinder should follow it under the same influence. 75 If, however, gravity of the parts is not alone, sufficient to overcome friction, etc., and insure that the cylinder shall assume the position determined by the cam-surface on the pattern-drum when the cylinder is 80 being lowered for tightening the stitches, the present invention furnishes auxiliary means, acting in conjunction with gravity, to cause the cylinder to assume, constantly, the proper operating position when the action of the pattern-drum is to lower it and without, in any way, preventing the raising of the cylinder when the tendency of the drum is to elevate it positively.

Prior to my invention, no practical means (so far as I am aware) has been provided for insuring proper positioning of the cylinder and its needles during the stage of shortening the stitches in the knitting operation, and the result has been that the fabric was sometimes looser than desired at such points. Various expedients have been attempted, but these have never been successful, so far as I am aware, and were, at best, mere makeshifts.

The device constituting my invention has in practice, on the contrary, been operated most successfully and efficiently, with the result that the normal tendency of the cylinder and its needles to vary from a re-

quired position, with resultant loose knitting, is effectually prevented.

While I have herein disclosed the device as an attachment for and applicable to a 5 Scott & Williams knitting machine, it is to be understood that I also contemplate building it in the structure as a permanent part of the machine and that it may also be utilized in conjunction with other makes 10 of machines.

It is to be understood that the machine as herein illustrated includes, inter alia, a machine-frame 1; a cylinder-rotating mechanism including a gear 2; pattern mechanism 15 comprising a pattern-drum 3; knitting instrumentalities comprising a needle-cylinder 4 and independently movable needles 5 slidably supported therein; cylinder-elevating mechanism associated therewith and 20 comprising a column 6 to which is attached one arm 7 of a two-arm lever 8, the other arm 9 of which carries a series of plungers 10 which cooperate with a series of cams 11 on the drum 3.

25 Encompassing the needle-cylinder is a cam-cylinder 12 which is stationary on the bed-plate 13 of the machine.

The foregoing elements, comprising the gear 2, a sleeve 14 integral therewith and 30 upon which the needle-cylinder 4 is removably mounted, and the cam-cylinder 12, are relatively stationary in a vertical sense. The needle-cylinder, however, is vertically movable to adjust the length of the stitch and 35 for other purposes, as well as to be free for removal from the machine.

To provide for the vertical movement of the needle-cylinder, the gear 2 is bored through, as at 15 (Fig. 1) in three places, to 40 receive three movable supports 16 in the form of hard steel pins, all of the same length. The bores 15 are in line with the bottom of the needle-cylinder which freely rests upon the upper ends of these pins.

45 The pins 16 rest upon and, by reason of the motion of the gear 2, rotate with respect to, a ring 18 at the top of the column 6 and having a suitably formed anti-friction surface, this ring having a bearing within a 50 depending cylindrical flange 19 of the bed-plate 13. The ring 18 is vertically movable within said ring 19 by the vertical movement of the column 6 concentric with the knitting axis which fits within the flange 55 19 at its upper end and upon which the ring 18 rests. As will now be evident, and as 60 fully described in said patent, the adjustment of the needle-cylinder by the means just described determines the length of the stitch formed by each needle during the knitting operation.

The needle-cylinder 4 is held to rotate with the sleeve 14 on the gear 2 by a feather 20 sliding in a vertical keyway 21 on the inner 65 wall of the cylinder. The cylinder may thus

be adjusted vertically with respect to the gear and sleeve 14 without disturbing its rotative adjustment with respect to the gear 2 or other elements of the machine.

70 Mounted on the upper end of the needle-cylinder is a web-holder ring or dial 22, and superposed thereon is a cam-ring 23 for operating web-holders 24, as usual, and as fully explained in said Scott patent.

75 Detachably secured to the bed-plate 13, as by a bolt 25, is a bracket 26 formed with a transverse groove 27 adapted to receive the bed-plate 13, the latter, on its periphery, being preferably provided with two indentations 28 into which short screws 29 extend 80 and which are threaded through the bracket 26. The screws 25 and 29 serve to hold the bracket rigid on the bed-plate.

85 Pivoted in the upper end of the bracket is a two-armed member 30 comprising a body-portion 31 bored, as at 32, to receive a cross-pin 33. Each of the arms 34 of the member 30 is formed with bosses 35 bored to receive a sliding-pin 36 having an enlarged lower end 37, for purposes presently 90 to be explained. The upper end of the pin is threaded to receive a nut 38 and a locknut 39. Encircling the pin is a spring 40 bearing against the enlargement 37 and the upper end of a recess 41 formed in the boss 35.

95 Threaded into the cross-pin 33 is a link 42 connected at its lower end to one end of a lever 43 fulcrumed at 44 on the bracket 26.

100 Means are associated with the device just described for actuating it; such means, preferably and as shown, including a rod 45 which extends through the bed-plate 13 and, at its lower end, is pivotally connected to one part 46 of a two-part lever 47 fulcrumed at 48, the other part 49 of the lever being 105 formed with a cam-engaging surface 50 adapted to ride on the face of the drum 3 and to be engaged by cams 51 and 51^a carried by the drum.

110 The upper end of the rod 45 contacts with the underside of an arm 52 forming a component of a switch-cam 53.

115 Operation: The operation of the structure above described will now be evident: When the parts are in the position shown in Fig. 1, each of the headed pins 36 (which I shall herein call presser-elements) bears, with yielding pressure, against the upper face of the cam-ring 23. When, however, the cam 51 on the pattern-drum 3, in the rotation thereof, disengages the end 50 of the lever 47, the latter will be caused to rock on its fulcrum 48, thereby actuating the rod 45 in a downward direction and, by reason of the fact that the free end of the lever 43 is disengaged from a screw 54 of a switch-cam-finger 55, the two-arm member 34 is rocked on its fulcrum, relieving the tension on the springs 40 which encircle the presser-elements. As soon as the extremity 50 of the 120 125 130

portion 49 of the lever 47 is engaged by and rides up on cam 51^a or 51, the lever will be rocked in the opposite direction, causing the rod 45 to be raised and, by reason of its engagement with the screw 54 in the switch-cam-finger 55 mounted on the upper end of the rod 45, the lever 43 is rocked on its fulcrum to operate the two-arm member and move the presser-elements against and with a yielding pressure upon the cam-ring.

During the movement of the two-arm member in either direction, the cross-pin 33 has a short sliding movement in the body-portion 31 of the member, this being necessary by reason of the position of the fulcrum of the lever 43 with respect to the connection to the lever of the link 42.

The extent of movement of the two-arm member under the influence of the lever 43 may be varied by screwing the link 42 farther into or out of the cross-pin, as the case may be.

The device, just described, by reason of the yielding pressure which it imposes upon the cam-ring, produces a follow-up action on the ring 23, on the associated ring 22 and, through it, positions the needle-cylinder 4 downwardly. This, in turn, through the pins 16 and the ring 18, pushes the column 6 downwardly. In other words, the device controls the cylinder which carries the web-holders over which the yarn is drawn. The length of each stitch is, of course, determined by the position of the knitting-ledge of the web-holders or sinkers with respect to the usual stitch-cam—not herein shown—operatively associated with the needle-cylinder.

As already stated, gravity alone is not always sufficient to cause the cylinder to lower to the position in which the cams on the drum 3 are intended to place it when the stitches are being tightened. Various conditions contribute to prevent this: For instance, the cylinder, during circular-work, revolves at a high rate of speed, being driven by the gear 2 through its sleeve and the feather 20 working in the keyway 21; and, as the cylinder has considerable weight, the driving-pressure on the surface of the feather is also considerable, so that, if the surfaces are not in perfect sliding condition, vertical movement of the cylinder would create friction which gravity, alone, might not be sufficient to overcome, especially in view of the inertia of the revolving cylinder. In such cases, the cylinder will lag behind that point where it should then be. It is at this stage that my device functions. It has a follow-up action, in that when in engagement with the cam-ring 23, it has a normal tendency to press it and the cylinder downwardly and, thus, supplements gravity in positioning the cylinder. In consequence, all back-lash between the cylinder and the pattern-drum is taken up and, as a result, the

mechanism which operates automatically to vary the length of the stitch in any required course or courses is maintained in the predetermined position. As already stated, the two-arm member, with its presser-elements, is held against the cam-ring through the lever 43 and its connection with the rod 45 and adjunctive parts.

When it is time for the cylinder to reciprocate, as in making the heel and toe of the stocking, the cam-ring must play between the limits required; and, under these circumstances, it is desirable to relieve the cam-ring from the pressure exerted thereon by this device. It is at this stage that the switch-cam has to be actuated, as well understood; and, by reason of the connection of the device to the mechanism which controls the position of this switch-cam, the two-arm member is rocked on its fulcrum and raises it and thereby relieves the tension of the springs 40 on the presser-elements simultaneously with the switch-cam being brought into action. As the cylinder will have been placed in the proper position before reciprocating knitting begins, and as the length of stitch required throughout the heel and toe work during this reciprocation remains constant, it is unnecessary for the device to be in operation at that time and it is, therefore, released in the manner described through the action of the switch-cam controlling mechanism. Furthermore, the driving pressure on the feather is continually being varied and relieved during reciprocation so that there is no driving pressure thereon at times and the cylinder is, then, free to fall by gravity into its proper position.

If it becomes necessary to regulate the degree of pressure on the cam-ring by means of the device, the tension of the springs 40 may be varied by tightening or loosening the nuts 38 and 39 on the pin 36. At the same time, the link 42 may also be adjusted in the cross-pin, as already referred to.

It is to be understood that my device constitutes one of a plurality of means for positioning the cylinder and thereby effect a tightening of the stitch: The weight of the parts constitutes one means, and my device constitutes another and includes instrumentalities for relieving it periodically, as occasion requires.

What I claim is:

1. In a knitting machine, a needle-carrying cylinder, needles therein, web-holders operatively associated therewith, a ring-member at the upper portion of the cylinder, and a follow-up device combinatively associated with and having a normal tendency to exert a downward yielding pressure on the ring-member to maintain the web-holders in a predetermined relation to the knitting-position of the needles.

2. In a knitting machine, a needle-carrying cylinder, needles therein, web-holders operatively associated therewith, a ring-member at the upper portion of the cylinder, a follow-up device combinatively associated with and having a normal tendency to exert a downward yielding pressure on the ring-member to maintain the web-holders in a predetermined relation to the knitting-position of the needles, and means for varying the relation of the device with respect to the ring-member.
3. In a knitting machine, a needle-carrying cylinder, needles therein, web-holders operatively associated therewith, a ring-member at the upper portion of the cylinder, a follow-up device combinatively associated with and having a normal tendency to exert a downward yielding pressure on the ring-member to maintain the web-holders in a predetermined relation to the knitting-position of the needles, and means for varying the relation of the device with respect to the ring-member periodically.
4. In a knitting machine, a needle-carrying cylinder, needles therein, web-holders operatively associated therewith, a ring-member at the upper portion of the cylinder, a follow-up device combinatively associated with and having a normal tendency to exert a downward yielding pressure on the ring-member to maintain the web-holders in a predetermined relation to the knitting-position of the needles, and means for varying the relation of the device with respect to the ring-member periodically and automatically.
5. A knitting-machine including a needle-carrying cylinder having a plurality of operating positions, means for actuating the cylinder, means associated with the cylinder and having a normal tendency to maintain the same in a predetermined operating position comprising a ring-member on the upper portion of the cylinder, a two-arm member, spring-controlled presser-elements carried by the two-arm member and yieldingly engageable with the ring-member, and actuating mechanism connected to the device for automatically varying its position.
6. A knitting-machine including a needle-carrying cylinder and a ring-member on the upper portion thereof, both the cylinder and member having a plurality of operating positions to vary the length of stitch, means associated with the member and having a normal tendency to maintain the same and the cylinder in a predetermined operating position including a member carrying a spring-actuated presser-element, and means for automatically varying the action of the member periodically.
7. A knitting-machine including a needle-carrying cylinder, means for actuating the cylinder to vary the length of stitch, a ring-member associated with the upper portion of the cylinder, cam-operating mechanism also associated with the cylinder, a presser-element having a yielding engagement with the ring-member at a plurality of points, and means interposed between the presser-element and the cam-operating mechanism whereby the former is actuated simultaneously with the latter.
8. A knitting-machine including a needle-carrying cylinder, means including a cam for actuating the cylinder to control the length of stitch, a plurality of means for tightening the stitch, and means for throwing stitch-tightening means out of action periodically.
9. A knitting-machine including a needle-carrying cylinder, a ring-member associated with the upper portion of the cylinder, means including a cam for increasing the length of stitch, a plurality of means for tightening the stitch including a yielding device operatively associated with the cylinder and engageable with the ring member, means for automatically throwing the yielding device out of action with respect to the ring-member, and means for varying the yielding effect of the device.
10. A knitting-machine including a needle-carrying cylinder, a ring-member on the upper portion thereof, a column associated therewith, means operating on the column to adjust the cylinder for varying the length of stitch, and means operating directly on the ring member and independently of the column to depress the ring member and thereby the cylinder to move the cylinder in the opposite direction.
11. A knitting-machine including a needle-carrying cylinder, means associated therewith for adjusting it to vary the length of stitch, a ring-member on the upper portion of the cylinder, and means operating directly on the ring-member and having a normal tendency to counteract the cylinder-adjusting means whereby back-lash between the cylinder and the adjusting-means is controlled.
12. A follow-up device for attachment to knitting-machines including a bracket, machine-securing means carried thereby, a two-arm member pivoted on the bracket, spring-controlled presser-elements adjacent the extremities of the member, means for adjusting the yielding action of the presser-elements, a lever fulcrumed on the bracket, and an adjustable link between the lever and the member.
13. A follow-up device for attachment to knitting-machines including a bracket, machine-securing means carried thereby, a two-arm member pivoted on the bracket, spring-controlled presser-elements adjacent the extremities of the member, means for adjusting the yielding action of the presser-elements.

ments, a lever fulcrumed on the bracket, and an adjustable connection between the lever and the member.

14. A knitting-machine including a needle-cylinder, needles, a pattern-drum for operating the cylinder and by which the length of stitch is determined, and positioning means including gravity for causing the cylinder to descend in relation to the drum, a ring-member on the upper portion of the cylin-

der, web-holders associated with the ring-member, and means operating on the ring-member and having a normal tendency to exert a downward yielding pressure thereon to maintain the web-holders in a predetermined relation to the knitting position of the needles. 15

In testimony whereof I affix my signature.

BENJAMIN HOFFMAN.
